[57] CLAIM

The ornamental design for a recycling container, as shown and described.

DESCRIPTION

FIG. 1 is a perspective view of a recycling container showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a perspective view of a second embodiment thereof;

FIG. 7 is a front elevational view thereof;

FIG. 8 is a left side elevational view thereof;

FIG. 9 is a right side elevational view thereof;

FIG. 10 is a rear elevational view thereof;

FIG. 11 is a perspective view of a third embodiment thereof;

FIG. 12 is a front elevational view thereof;

FIG. 13 is a left side elevational view thereof;

FIG. 14 is a right side elevational view thereof; and,

FIG. 15 is a rear elevational view thereof.

The undisclosed bottom is flat and unornamented.

The broken line showing is for illustrative purposes only and forms no part of the claimed design.
